(57) **CLAIM**

The ornamental design for a bottom tray for shopping cart, as shown and described.

DESCRIPTION

FIG. 1 is a top perspective view of a bottom tray for shopping cart showing our design.

FIG. 2 is a top view thereof, the bottom view being identical thereto.

FIG. 3 is a front elevational view thereof.

FIG. 4 is a rear elevational view thereof; and,

FIG. 5 is a left side elevational view thereof, the right side being a mirror image thereof.
